J. Willard.

Shot Machine.

Patented July 10, 1830.

July 17, 1830

William Willard of the City & State of Maryland,

Letters Patent. X 6074

The schedule referred to in these Letters Patent and making part of the same, containing a description in the words of the said Sabine Willard himself of his improvement in the machine for making shot, musket and rifle balls called Willard's Patent Shot-machine.

To all to whom these presents shall come

Be it known that I Sabine Willard of the City of Baltimore and State of Maryland have invented a new and useful machine for making shot musket and rifle balls. called Willard's Patent Shot-machine; and that the following is a full & exact description of the construction and operation of the said machine as invented by me. — The machine consists of two parts the casting bench by which the shot or balls are formed and the Rolling machine or frame by which they are made spherical by rolling and compression. — In the annexed drawings fig. 1, 2, 3 & 4 are views of the casting Bench, & its machinery fig. 1 being an upright view and fig. 2. a birds eye view of the same It consists of a substantial wooden frame or bench, the top part of which form an inclined plane upon which and in the space in dunes between them slides the iron round plate (P. L.) which is furnished on its upper side with a track, (dotted in fig. 3) that works in a fissure in the edge of the large cog-wheel (R) which is acted on by the crank (I) of the small cog-wheel (C) and causes the round and its fixture to move up and down the plane at the pleasure of the operator. To relieve the fixture occasioned by the sliding of the round plate either on the top or sides are placed under it as shown in fig. 1 and fig. 3, and as shown the iron round plate which is in two pieces, more distinctly, fig. 3 being

the lower part which is made fast by two hings, a. b. to a block of wood faced with sheet iron or to an iron plate, it has its upper surface fitted as seen in the figure with a convenient number of moulds each being a hemisphere of the shot, or ball, that is to be moulded. The lower end (C, of the block or plate, is hollowed out into a valley or shoot, Fig. 4. The upper part or lid of the mould which is about half the thickness of the diameter of the shot or ball, is fitted on its under side, so as to match the lower plate, and is perforated opposite to these pits with small holes or gates which communicate from the upper side with the hollow spheres formed by the pits in the plate when laid together the plates being also supplied with an adjusting pin (p) and a levelled point (P), so as to bring the hemispherical pits exactly opposite to each other, and the upper plate is prolonged into a hooked form as seen in the drawing Fig. 4 which serves for a handle, and it is a sheet iron ing or hopper without a bottom its lower edge is attached to a square trap frame having a knife of (Fig. 3.) placed obliquely across the edge, of which lays in the same plane, with the lower surface of the trap frame; the frame projects over the outside of the box, and the outer edges corresponding to the sides of the mould, are turned down; or strong pieces are secured theron for the purpose of keeping it on the mould when the latter is moving up the plane. The frame also has two small fixed points (L.L.) to prevent the hopper from following the mould, by stopping it against the iron brace hooks, D, which are attached to the bar or box, D, by the regulating screws, and nuts n, or, from the top of which they branch and rising along a groove, in the inner or outer sides (as shown in the drawing) of the top rail of the brace are turned inward, and downward and when the bar D, is act on by the lever O, to which the weight W is suspended, hangs on the upper surface of the trap frame of the hopper and keeps it

35

is accommodated with the surface of the mould plate. G is a
 long lever, connected by an axis with the compound lever
 H, and is only intended to relieve the pressure of the brace
 hooks, when the hopper is to be removed by throwing it
 back, into the notch (v Fig 2) on the side of the top rail
 of g. g. is a strip of plank, or sheet iron, attached to the outer
 side of the top rail and rising a few inches above it has
 a small spoon g. at its lower end, forming together with
 the top surface of the rail, which is faced with sheet iron
 and a very narrow strip of that iron fixed across on the
 rail next to the mould, a shot to convey the shot, when cast
 as will be seen, in using the casting bench, the mould
 is moved down the plane, until it is stopped by the spring
 notch (d) on the side of the mould, which was omitted in
 the description against a fixed pin (L) in the top of the rail
 The hopper is then placed on the mould and forced down
 by the brace hooks by throwing out the lever (G) A sufficient
 quantity of melted lead for a cast is thrown into the hopper
 the crank F is turned, the hopper remains stationary and
 the mould is made to ascend the plane till the spring notch
 on its side takes hold on a fixed pin (L) at the upper part
 of the plane during this motion the moulds fill, and the
 oblique knife f. cleans the lip of the mould also the distance
 is so regulated that the lower part of the hopper at the end
 of the motion projects over the shot- or valley (S.) and the
 lead which may still remain in the hopper in a fluid
 state runs off is caught by the boy in a ladle and returned
 to the kettle again the lever G is then thrown back into the
 notch v. which relieves the pressure of the braces on the
 hopper the latter is then lifted off for which purpose it is
 supplied with a handle w. after which the mould is dis-
 charged by throwing it upon its edge (for which purpose the
 stops mentioned in the description are intended) in the notch

formed along the top of the rail and striking it a blow or two with a stick. It may be proper to mention that a little talcum may be occasionally applied to the muscle when hot.

The Rolling frame consists of several parallel wooden bays or troughs A.A. &c. Fig. 4 supported on frame T.T. so as to have a gentle inclination also parallel and in the same plane with the bays two strong pieces of thick black, or jute h.h. are set up edge-wise and strongly fastened together forming a bearing for a system of equal spur wheels the journal of every other one of which f f f f f. &c. projects on both sides and being square is connected by lines of square connecting bands or tubing m.m. &c. to the ends l.l.l.l. &c. of the square journals of the rolling S.S.S.S. the opposite bands are contained in the trough A.A. and the square journals of the rollers are contained in a similar manner to the rollers of the next trough and so on so that when the middle spur wheel at C is made to revolve by means of the great wheel, R. (The strong bearings of whose axle (Q) are omitted in the drawing) the rollers in all the bays, revolve together, and in the same direction. In place of spur wheels, wooden pulleys may be substituted with a separate band to each winding on a drum fixed on the axle (Q) of the great wheel which will reduce the friction considerably in order to a more minute description of the rollers contained in the bays Fig. 5. & 6 are varied views of a part of the bar in fig 6. which is a birds eye view (A) is the roller, made of cast iron a.a. its projecting square journals f f f f &c. are longitudinal half round or nearly half round grooves which may be D. 4. or 5 in number, according to the size of the shot, or balls; corresponding to these grooves are cast iron dies r.r. &c. &c. adapted to the extremities in circumference of the roller, and each being something more than a quadrant so that each pair of dies embrace more than half the circumference of the roller and when they are at

up against on the trough and opposite this opposite groove in the roller a cylindrical ring is formed by these grooves and the groove of the roller. The dies are stopped in freely and are only confined by the regulating screws 3.3.3.3. h. h. &c. fixed in the upright wooden plane M. M., and the bottom of the box which upright pieces also serve as points of attachment for the sheet iron plates or 'lions' q. q. Fig. 5. between the rollers upon which the shot roll from one roller to the other, and in passing over them change their position, also a small plate of sheet iron (M. M.) is let into the sides of the shot to prevent the shot from passing over the roller; Fig. 7 & 8. are side views of a roller and the concave surface of the dies of one side thereof. The operation of the rolling frame is as follows: when the shot are cast as above described they are first braded to separate the very defective ones if any they are then thrown into a barrel with a small quantity of black lead, after being agitated for a short time for the purpose of coating them slightly with the lead, which prevents them from adhering to each other in the rolling process, they are poured in proper quantities into small hoppers (not shown in the drawing) at the highest ends of the box A. A. & the rollers being set in motion the shot are taken in by the grooves of the first roller, partly rounded and thrown out on the sheet iron plate below it they descend to the next roller in passing through which their shape is still further improved and so on till passing through the 5. and last roller, which is the number I use, and have found to be sufficient, they come out ready for polishing. the manner of doing which it may be necessary to mention, as I have found the common method used for cast shot not to answer so well. - It consists simply in a wire wire down with iron heads having jagged and a variety of very odd notches of which it may be provided, a quantity of

X 6074

of the shot are put into it and a small quantity of
lead is then turned till the shot has the desired form
after which they are taken out and hardened in the common
way, in other what I claim as new and as my invention
is the casting Bench and Rolling frame and their machinery
as herein described applied to the purpose specified.

Given under my hand and seal this 5th day of July 1838
